UNITED STATES PATENT OFFICE.

CALVIN A. BONNER AND EDWARD E. EUCHENHOFER, OF DAYTON, OHIO,
ASSIGNORS TO DANIEL M. STEWART, OF XENIA, OHIO.

ORE-CONCENTRATOR.

SPECIFICATION forming part of Letters Patent No. 737,326, dated August 25, 1903.

Application filed March 7, 1902. Serial No. 97,023. (No model.)

To all whom it may concern:

Be it known that we, CALVIN A. BONNER and EDWARD E. EUCHENHOFER, citizens of the United States, residing at Dayton, Montgomery county, Ohio, have invented certain new and useful Improvements in Ore-Concentrators, of which the following is a full, clear, and exact description.

The object of our invention is to provide a concentrator consisting of a stationary bed having a flexible section upon which is exerted from below a motive fluid-pressure, preferably compressed air, and regulated by means of a cylinder and piston; and the invention consists of the construction and arrangement hereinafter described and claimed.

In the drawings hereto attached, Figure 1 is a detail of a part of the device. Fig. 2 is a vertical sectional view of the machine, the cylinder being shown in elevation. Figs. 3 and 4 show the top and bottom view of the lower section of the device to which the valve-cylinder is attached, and Fig. 5 shows a section of the valve-cylinder arrangement.

We employ an ordinary frame 1 for the sides of the concentrator-top which surrounds the diagonal strips 2 and 3. The diagonal strips 2 and 3 are such as are ordinarily used for such purposes. Underneath these diagonal strips we place section 5, which is composed of some flexible material and which will permit air to pass through it. To support this section 5, we place the frame 4 (fully shown in Fig. 1) underneath it. This frame is composed of a number of ribs 4, which are arranged at regular intervals, the object being to allow the air, as will be more fully explained, to pass through the space 6 between the ribs. We fasten this frame 4 to the corrugated section 7, which is employed to assist in disseminating the air-pressure up to and through section 5. The corrugated section 7 is constructed as shown in Figs. 3 and 4. Fig. 3 shows a section of the top view, and Fig. 4 shows a section of the same in an inverted position. It has a groove 8 extending around its outer edge and a number of small cross-grooves 10 extending across its top. In the center of this bottom and underneath 50 there is a collar 11, forming an opening from

which extend and diverge air-passages 9, which connect with groove 8. Directly under the opening formed by collar 11 in this corrugated section is attached the cylinder-valve arrangement for causing the motive pulsations and vibrations up to and through the flexible section 5. This cylinder is composed of two parts, but may be cast integrally, the upper part 15 being smaller than the lower part 18. Within the smaller cylinder 15 is a small piston 13, and within the large cylinder 18 is a large piston 27. The motive fluid-pressure is exerted upon the large piston 27 into the space 28 by means of the inlet-pipe 16, which is connected with any means which may be employed for this purpose. When the piston 27 is forced back by this pressure, the air passes to the rear part 29 of the cylinder by means of the air-passage 30, and the piston is then driven forward. The pipe 17 is an outlet for the air, and 26 is the bottom and end of the large cylinder. This valve-cylinder, Fig. 5, arrangement is fastened to the corrugated section 7 by means of a flange 25 and the bolts, as shown in vertical section 75 Fig. 2.

The intake-pipe 14 is for the purpose of conveying and supplying a pressure of air up to and through the flexible section 5, through the air-passages 9 and 8, corrugations 10, and diagonal passages 6. The smaller piston 13 acts as a valve to open and close the opening of the pipe 14. As the piston 13 travels forward and backward, opening and closing the pipe 14, the compressed air is allowed to ascend from intake-pipe 14, through the collar, air-passages 11, 9, and 8, and corrugations 10, up through diagonal passages 6, and through the flexible section 5. The working of this smaller piston 13 causes a pulsation or vibration on the flexible section 5. The air when forced against flexible section 5 of the machine permeates or passes through it and assists thereby in the concentration. For supporting the device any substantial frame may be used, the support herein being designated by 23 having a top 21, at each end of which are adjusting-screws 19, and each are adapted to be raised or lowered to cause the desired angle for the concentrator-bed which they 100

support. These adjusting-screws are each provided with a universal ball-and-socket joint 20 at their upper ends and connecting with the bottom of corrugated section 7. These 5 screws extend down through and work in nuts 22. They each are provided with a lock-nut 31 and a hand-wheel 32 for raising and lowering.

Having fully described our invention, what 10 we desire to secure by Letters Patent is—

1. In an ore-concentrator operated by means of motive fluid-pressure a bed having diagonally-arranged strips placed over a flexible section which is supported by a ribbed 15 frame resting upon a corrugated bottom having air-passages diverging from an opening in its center, a cylinder arrangement placed under the opening of said corrugated bottom and said cylinder consisting of an enlarged 20 part in which is operated a large piston to the upper part of which is attached a smaller piston which acts as a valve opening and closing the intake-pipe for the fluid-pressure, and

means for holding and regulating the position of the machine.

2. In a device for concentrating ores by motive fluid-pressure, a bed having diagonally-arranged strips placed over a flexible section, a ribbed frame supporting said section, a corrugated bottom supporting said frame, said 25 corrugated section having grooves upon its center for disseminating the pressure which is discharged into them by means of passages extending from an opening at the center of said section and said opening being placed 30 over a cylinder arrangement for conducting the pressure and causing the pulsations of the pressure.

In witness whereof we have hereto set our hands in the presence of two witnesses.

CALVIN A. BONNER.
EDWARD E. EUCHENHOFER.
